(57) **CLAIM**

The ornamental design for a docking station for computing devices, as shown and described.

DESCRIPTION

FIG. 1 is a front perspective view of a docking station for computing devices showing our new design;

FIG. 2 is a rear perspective view thereof;

FIG. 3 is a front view thereof;

FIG. 4 is a rear view thereof;

FIG. 5 is right side view thereof;

FIG. 6 is a left side view thereof;

FIG. 7 is a top end view thereof;

FIG. 8 is a bottom view thereof;

FIG. 9 is a front perspective view of a second embodiment thereof;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top end view thereof; and,

FIG. 16 is a bottom end view thereof.

The interior of the phantom portions of the embodiments form no part of the claimed design.
